UNITED STATES PATENT OFFICE.

HAROLD W. SHONNARD, OF UPPER MONTCLAIR, NEW JERSEY, ASSIGNOR TO CRUCIBLE STEEL COMPANY OF AMERICA, OF PITTSBURGH, PENNSYLVANIA, A CORPORATION OF NEW JERSEY.

TORPEDO STEERING UNIT.

1,296,329.

Specification of Letters Patent.

Patented Mar. 4, 1919.

Application filed April 30, 1917. Serial No. 165,430.

To all whom it may concern:

Be it known that I, HAROLD W. SHONNARD, residing at Upper Montclair, in the county of Essex and State of New Jersey, a citizen 5 of the United States, have invented or discovered certain new and useful Improvements in Torpedo Steering Units, of which improvements the following is a specification.

10 The object of my invention is to improve the construction and operation of steering units for marine automobile torpedoes.

Such torpedoes, as they are now constructed, include two steering units, a gyroscopic 15 apparatus for controlling the vertical rudders, and a driving gear for controlling the horizontal rudders. While, in the broader aspect of my invention, some of the features are applicable alike to both such steering 20 units, in its more specific aspects it is limited to gyroscopic apparatus, and is so illustrated in the accompanying sheets of drawings.

Figure 1 of the drawings is a longitudinal 25 vertical sectional view of a torpedo and a gyroscopic steering unit contained therein; Fig. 2 a combined horizontal section and plan view of the steering unit, the plane of view being indicated by the broken line 30 II-II, Fig. 1; and Figs. 3 and 4 views similar to detached portions of Fig. 1, but showing modifications of construction.

In the operation of torpedoes, such as contemplated herein, highly heated motive fluid 35 is used to drive the turbine or other propelling engine, and the exhaust gases from such engine usually pass into the torpedo afterbody, and from thence they escape through a suitable outlet at the tail of the torpedo.

40 These exhaust gases in the afterbody necessarily heat to a considerable extent the apparatus contained therein, including the two aforementioned steering units. It has been found that a requisite to uniformity of operation of these units is that they be maintained at a substantially constant temperature 45 throughout the run of a torpedo. If a gyroscope, balanced and otherwise adjusted at a given temperature, becomes unduly heated or cooled, it will, when spun, usually precess considerably beyond the permissible limits, such precession being due to the effect, on the gyroscope bearings and balance, of the temperature expansion or contraction.

55 Furthermore, in the case of electrically spun

gyroscopes, excessive heating is liable to char or otherwise injure the insulation of the windings. With respect to the other steering units, namely, the driving gear, it has been found that the heating of the air in the 60 spring compartment increases the pressure upon the diaphragm and hence causes the torpedo to travel at a gradually increasing depth rather than at approximately the predetermined desired depth. 65

In view of the foregoing considerations, one of the specific objects of my invention is to provide, for such steering units, a water-jacketed housing which may be readily mounted within or removed from a torpedo, 70 and whereby no special connections need be made for placing the water jacket in communication with the water of submersion.

In the specific illustrative embodiment of 75 my invention the bottom of the hull 1 of the torpedo is provided with a suitable opening to receive the steering unit, and, adjacent to such opening, there is a suitable support 2 to which the unit may be attached. As already stated, the steering unit 80 shown herein is a gyroscope, and it will presently appear more fully that it is of the type that may be spun electrically. The unit is mounted within a protecting housing 3 which is provided with a water-jacket 4. 85 To the end that there may be a ready circulation, through such jacket, of water of submersion, and, furthermore, that no special connections need be provided for this purpose, the lower end of the housing is provided with inlet and outlet ports 5 and 6, respectively. As shown in Figs. 1 and 2, the inlet ports 5 communicate at their upper ends with the fore portion of water-jacket 90 chamber of the housing, and at their lower end with a recess or passageway 7 formed in the support 2. In a similar manner the outlet ports 6 communicate at their upper ends with the aft portion of the water chamber 95 and at their lower ends with passageways 8. 100 By such construction and arrangement, the speed of the torpedo will have the effect of simultaneously impelling or forcing water through the passageways 7 and ports 5 into the fore portion of the water jacket and of 105 withdrawing, by a suction action, the water from the aft portion of the jacket. Thus there is provided an adequate means for causing a continuous flow of water through 110 the jacket.

In Fig. 4 there is shown a modification in the construction of ports and passageways. The support 2^a is provided with substantially U-shaped passageways 7^a which register with similarly shaped ports 5^a formed in the housing 3^a. In both forms, however, it will be observed that, by locating the ports at the lower end of the water-jacketed housing, the water-jacket chamber 10 is placed in communication with the water of submersion immediately upon attaching of the housing 3 or 3^a to the support 2 or 2^a, as by means of bolts 9 or 9^a, and without making further connections for the purpose.

15 While not shown herein, it will be readily understood that the construction just explained is applicable to housings for driving gears. Its applicability to such use is shown in my application Serial No. 176,094.

20 Another feature of my invention has to do with the construction of gyroscopic steering units. In view of the increased range requirements for torpedoes, it has been found necessary to make provisions for a longer 25 effective spinning of the gyroscope. This has been accomplished, first, by improving the general construction of the gyroscope and its spinning mechanism, and secondly, by constructing the gyroscope as an electric 30 motor and providing means for continuously supplying current to it after the initial spinning impulse, which spinning impulse has usually been effected either by an electric current or by mechanism coördinated with the torpedo-propelling mechanism.

The specific object of this further feature of my invention is to provide a gyroscopic steering unit which will be simple and inexpensive in construction, compact in form, and which may, as a whole, be readily mounted within and be removed from a torpedo.

In the practice of my invention, I provide 45 an electric motor gyroscope with spring actuated mechanism for effecting its preliminary spinning, and also provide a source of electrical energy for supplying current for the continuous spinning of the gyroscope. Preferably, these three essential elements are secured to a common frame which is 50 removably attached to the hull of the torpedo, so that the gyroscope steering mechanism may be removed as a unit when necessary to make adjustments, tests or repairs.

While the electric motor gyroscope may be of any desired form or construction, it is preferably an induction motor similar to that shown and described in my U. S. Patent 60 No. 1,163,606, the housing 10 of the gyroscope shown herein corresponding with the housing 3 of that of said patent and forming the inner gimbal of the gyroscope. The outer gimbal 11 is pivotally mounted in 65 suitable supports 12 and 13 attached to the

housing or main supporting frame 3, and is provided with a member 14, adapted to operate a valve 15 for controlling a steering engine 16 of the usual, or any desired, type mounted upon the housing 17. The valve 70 15 is suitably secured to an angle fire indexing mechanism including a segmental worm gear 18, adapted to be turned to any desired position by means of a worm shaft 19, rotatably mounted in the housing 3 and provided with a wrench-engaging head 20. The valve 15 and indexing mechanism shown herein are the same as the corresponding elements shown and described in my U. S. Patent No. 1,030,134, and hence need no further explanation herein. 80

For the preliminary spinning of the gyroscope I preferably provide a spring impelled mechanism or motor, which, in all essential respects, may be the same as the 85 Obry gyroscope fully shown and described in U. S. Patent No. 621,364. Such mechanism is simple and light in construction and is capable of spinning a gyroscope to a speed sufficient to cause it to properly control a 90 torpedo for a short distance, that is to say, for a distance less than the present long range requirements. By effecting the preliminary spin of the gyroscope by such spring actuated mechanism, and the continued spinning by supplying, in a manner presently to be explained, an electric current to the gyroscope, a gyroscopic steering unit 95 of unusual simplicity and effectiveness is afforded.

The essential elements of the spinning mechanism shown herein includes a rotatably mounted shaft 21, to the upper end of which there is attached a hollow conical gear segment 22 adapted to mesh with the conical 105 gear 23 attached to the outer end 24 of the gyroscope rotor, which rotor projects through the housing 10. Surrounding this shaft there is a coil spring 25 secured at its upper end to the shaft and at its lower 110 end to a fixed support 26. At the lower end of the shaft there is attached a toothed disk 27 adapted to be engaged by a spring-pressed latch 28 secured to a rotatable shaft 29, which shaft in turn is, through arm 30, rod 115 31, and arm 32, suitably attached to the starting latch 33. The gyroscope is suitably locked by means of a spring-pressed pivoted lever, having a locking arm 34 and a releasing arm 35, the shaft 21 being provided with a cam finger 36, which, upon the rotation of the shaft, trips the lever 34, 35 and holds it in unlocked position. To stop, at the required position, the rotation of the gear 22, a suitable cushioning cylinder 37 125 may be attached to the housing 3. The construction of this stopping mechanism, as well as the detail construction of the other parts of the preliminary spinning mechanism are similar to the corresponding parts 130

of the apparatus shown in the above mentioned Obry patent, and need not be shown herein.

In the operation of the spring motor preliminary-spinning mechanism, the motor is set by turning the shaft 21 until the parts are in the position indicated in the drawings, the gyroscope being locked by the arm 34. When the starting latch 33 is tripped, 5 the latch 28 releases the disk 27 so that the gear revolves rapidly through a partial revolution and thus spins the gyroscope rotor. At the end of the spin the gyroscope is unlocked by the finger 36 engaging the lever 10 arm 35, and the motor stopped by the cushioning cylinder 37.

In case it is desired to effect the preliminary spinning of the gyroscope prior to the launching of the torpedo for the purpose of 20 practising the method of fire control according to my U. S. Patent No. 1,035,647, the tripping of the latch 33 may be effected by an electro-magnet in the manner shown particularly in Fig. 3 of my U. S. Patent No. 25 1,163,606, or by an equivalent device.

For supplying the electric motor gyroscope with current to effect a continued spinning thereof, I preferably mount, upon the housing or frame 3, a source of electrical 30 supply in circuit with the gyroscope. While, as shown in Fig. 1, such source is preferably a generator or magneto, it may be a storage battery as shown in Fig. 3.

Referring to Fig. 1, the rotor 38 of the 35 generator 39 may be provided with a spur gear 40 adapted to mesh with a pinion 41 keyed to the propelling shaft 42. The parts are so arranged relatively to each other that, when the steering unit is mounted within 40 the torpedo, the gear 40 will mesh with the pinion 41. Thus, the mere operation of placing the unit in the torpedo establishes a driving connection between the torpedo-propelling mechanism and the generator, so 45 that, when such propelling mechanism is started, current is generated for, and supplied to, the gyroscope. The generator casing is water jacketed in the manner indicated at 61.

50 The electric current may be carried from the generator through conductors 43 and 44 to the gyroscope, and the electrical connection through the gimbals to the electric motor may be the same as those shown particularly in Fig. 5 of my U. S. Patent No. 55 1,192,468 for an electric motor gyroscope.

Fig. 3, as already stated, shows a storage battery 45 mounted on the housing or frame 3. That current may be supplied to the 60 gyroscope only after the spring motor has effected the preliminary spin, the circuit is normally broken, and means are provided to close it at the end of such spin. For this purpose the upper end of the shaft 21 may 65 be provided with a contactor 46 so disposed

that, at the end of the operation of the spring motor, it will afford electrical continuity between two terminal contactors 47 in the conductor 48. The other conductor 49 leads directly to the gyroscope.

70 It will be observed of both forms that the gyroscope, the preliminary spinning motor and the source of electrical supply are all mounted on a single frame, thereby affording a gyroscopic steering unit which may be 75 readily mounted within or removed from the torpedo. In mounting the unit in the torpedo it is necessary to make several small connections within the torpedo hull, namely, a pin connection 50 between the arm 30 and 80 the starting latch rod 31, a pin connection 51 between the steering engine piston rod 53 and the rudder rod 54, and a union joint connection 55 between the steering engine 16 and a conduit 56 for supplying compressed 85 air or other motive fluid to such engine. As is usual, the torpedo hull is provided with a hand hole 57 so that access may be had to the interior of the torpedo to make these 90 connections.

95 According to the provisions of the patent statutes, I have described the principle and operation of my invention together with the construction which I now consider to represent the best embodiment thereof. However, I desire to have it understood that my invention may be practised with other forms of construction than that shown herein.

I claim as my invention:

1. The combination with an automobile 100 torpedo having its hull provided with an opening to receive a steering unit, of a steering unit support adjacent to such opening and secured to the torpedo hull, and a steering unit secured to such support, said unit 105 including a water-jacketed housing provided at its lower end and adjacent to said hull opening with ports for admitting water to and discharging it from said jacket, said ports being adapted solely upon the attachment of said unit to said support to place the water-jacket portion of said housing in communication with the exterior of the torpedo.

110 2. The combination with an automobile torpedo having its hull provided with an opening to receive a steering unit, of a steering unit support adjacent to such opening provided with a passageway open at one end to the exterior of the torpedo hull, and a steering unit secured to such support, said unit 115 including a water-jacketed housing provided at its lower end with a port communicating at one end with the water-jacketed portion of said housing and at its other end 120 registering with said passageway, such communication being effected solely by the attachment of said housing to said support.

125 3. The combination with an automobile torpedo having its hull provided with an 130

opening to receive a steering unit, of a steering unit support adjacent to such opening, and a steering unit secured to such support, said unit including a water-jacketed housing provided at its lower end with water inlet and outlet ports facing, respectively, fore and aft of the torpedo, said ports being adapted solely upon the attachment of said unit to said support to place the water-jacket portion of said housing in communication with the exterior of the torpedo.

4. The combination with an automobile torpedo having its hull provided with an opening to receive a steering unit; of a gyroscopic steering unit comprising an electric motor gyroscope, a spring motor for effecting the preliminary spinning of said gyroscope, a source of electrical energy for supplying said gyroscope with current for a continued spinning thereof, and a common frame for said gyroscope, spring motor and source of electrical energy; said unit being removable as a whole through said opening in the hull.

5. The combination with an automobile torpedo having its hull provided with an opening to receive a steering unit; of a gyroscopic steering unit comprising an electric motor gyroscope, a spring motor for effecting the preliminary spinning of said gyroscope, a generator for supplying said gyroscope with current for a continued spinning thereof, and a common frame for said gyroscope, spring motor and generator; said unit

being removable as a whole through said opening in the hull.

6. The combination with an automobile torpedo having its hull provided with an opening to receive a steering unit, and with propelling mechanism including a rotatable member provided with a driving gear; of a gyroscopic steering unit comprising an electric motor gyroscope, a spring motor for effecting the preliminary spinning of said gyroscope, a generator for supplying said gyroscope with current for a continued spinning thereof, the rotor of said generator being provided with a pinion meshing with said driving gear, and a common frame for said gyroscope, spring motor and generator; said unit being removable as a whole through said opening in the hull.

7. In an automobile torpedo, the combination of steering mechanism, an electric motor gyroscope for controlling said mechanism, a spring motor for effecting the preliminary spinning of the gyroscope, a source of electrical energy within the torpedo for supplying the gyroscope with current for its continued spinning, and a common frame for said gyroscope, spring motor and source of electrical energy.

In testimony whereof I have hereunto set my hand.

HAROLD W. SHONNARD.
